US0D1026978S

(12) **United States Design Patent** (10) **Patent No.:** **US D1,026,978 S**
(45) **Date of Patent:** **** May 14, 2024**

(54) **ELECTRIC WOOD SPLITTER**

(71) Applicant: **INTRADIN (HUZHOU) PRECISION TECHNOLOGY CO., LTD.**, Huzhou (CN)

(72) Inventors: **Gaofeng Wang**, Huzhou (CN); **Chenliang Yuan**, Huzhou (CN)

(73) Assignee: **INTRADIN (HUZHOU) PRECISION TECHNOLOGY CO., LTD.**, Huzhou (CN)

(**) Term: **15 Years**

(21) Appl. No.: **29/819,590**

(22) Filed: **Dec. 16, 2021**

(51) LOC (14) Cl. **15-09**

(52) U.S. Cl. USPC **D15/127**

(58) **Field of Classification Search**

USPC D15/127; D8/1, 7; 144/195.1, 193.1
CPC B27L 7/00; B27L 7/06

See application file for complete search history.

CLAIM

The ornamental design for an electric wood splitter, as shown and described.

DESCRIPTION

FIG. 1 is a front, left, top perspective view of an electric wood splitter showing our new design;

FIG. 2 is a back, right, bottom perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is a partially enlarged view of FIG. 1; and,

FIG. 10 is a partially enlarged view of FIG. 3.

The broken lines shown on the drawings depict portions of the electric wood splitter that form no part of the claimed design.

1 Claim, 10 Drawing Sheets
